UNITED STATES PATENT OFFICE.

JAY R. CORBETT, OF NEW WILSON, OKLAHOMA.

SPUDDING-SHOE.

1,275,395.

Specification of Letters Patent. Patented Aug. 13, 1918.

Application filed April 18, 1918. Serial No. 229,300.

To all whom it may concern:

Be it known that I, JAY R. CORBETT, a citizen of the United States, residing at New Wilson, in the county of Carter and State of Oklahoma, have invented certain new and useful Improvements in Spudding-Shoes, of which the following is a specification.

This invention relates to well drilling implements; and has particular reference to spudding shoes.

The object of the invention is to provide an improved form of spudding shoe which may be employed with all ropes and cables which may be found in a well drilling outfit. In outfitting a drill rig, a well digger frequently finds it necessary to buy such hemp or wire cables as are found in stock in supply houses where he may be operating, and in this manner he gathers a number of cables of different sizes and character. Heretofore to the best of my knowledge, it has been necessary for a well digger to have on hand a spudding shoe capable of use with each size cable which it might be necessary to bring into use, owing to the fact that spudding shoes each carry upon their outer faces a single groove which is cut to receive a particular size cable. It is therefore the intention of this invention to provide a spudding shoe which may be adapted for use with any sized cable by changing the grooved face of the shoe with an assorted number of faces which accompanies each shoe, so that the particular cable then in use may be accommodated.

With the above general object in view and such others relating to the details of invention as may hereinafter appear, my invention will now be fully set forth and described reference being had to the accompanying drawings, in which like reference characters indicate like parts throughout and:—

Figure 1 is a fragmentary elevational view showing the manner of use of the spudding shoe.

Fig. 2 is a vertical longitudinal section through the improved device.

Fig. 3 is a perspective view of one of the interchangeable faces.

Fig. 4 is a transverse sectional view.

Fig. 5 is a perspective view of a rope holding device.

Referring more particularly to the drawings, 1 represents the body of the shoe which may be of wood, metal or other suitable material, said body 1 being generally arcuate in form, but upon its rear or concave side having the bearing projection 2 within which is cut the transverse bearing groove 3. The bearing groove 3 receives the transverse journal 4 of a clevis or yoke 5, said clevis 5 having the legs 6 which extend forwardly across the sides of the body 1, and at their extremities are outturned into the hooks 7. The bearing 4 is held in place by means of a retaining plate 8 secured into position over the bearing grooves 3, so as not to interfere with the ability of the clevis 5 to oscillate toward the ends of the body 1.

The hooks 7 formed on the ends of the legs 6 are open rearwardly, and are shaped to receive the trunnions 9 which extend beyond the sides of a rope holding block 10, the latter consisting of a wedge-shaped body having a groove extending longitudinally of its beveled faces and across the larger end of the block as at 11, so that a loop formed in the end of a rope or cable 80 may be engaged thereover. After such a loop has been engaged over the groove 11 the trunnions 9 may be inserted into the hooks 7, and it will be obvious that as long as tension is maintained upon the cable, 85 which is indicated at 12 in Fig. 1, the connection between the cable and the spudding shoe will be maintained, but as soon as the tension on the cable 12 is released, the rope will be instantaneously disengaged from the 90 spudding shoe, and the latter is then free to be removed from the cable 13 upon which it might be riding.

The body 1 carries, along the corners of its convex face, a pair of forwardly projecting parallel flanges 14 which form a pocket into which the removable face 15 may be snugly seated, said face 15 consisting of an elongated arcuate plate whose rear face follows the curvature of the rear face 100 of the convex body 1 and whose outer face is provided with a groove 16 dimensioned to receive the particular cable for which the plate is constructed. The extremities of the

face or plate 15 are provided with the rearwardly extending ends or lugs 16' which overlie the extremities of the body 1, and are drilled to receive the set screws 17, 5 which enter the body 1 and firmly hold the face 15 in position for use. While only one of the faces has been indicated in the drawings they may be obviously furnished in any number of sizes, which will accord with the 10 requirements of the average well digging outfit, and when the shoe is to be used, it might be quickly arranged to operate upon the particular cable 13 which may be in use. There is thereby avoided the necessity of 15 changing the cable 13, or carrying in the outfit a number of the spudding shoes which in themselves are more or less bulky and heavy. Furthermore, the present construction permits the body 1 to be made of a 20 lighter and less durable material than is necessary, as in the present usage, when the shoes are constructed with integral faces.

Furthermore, by reason of the improved

construction of the clevis and rapid attaching means the device is readily attached or 25 removed from the rigging, with a consequent saving of time to the user.

What I claim as my invention, is:—

1. A spudding shoe including a body, and an arcuate removable bearing face carried 30 by the body.

2. A spudding shoe including a body, and a removable arcuate face carried by the body, said arcuate face having a cable receiving groove formed therein, and rearwardly projecting lugs on the ends of the face for attachment to the body.

3. A spudding shoe including a body, a clevis carried by the body, said clevis having legs overlying the sides of the body and 40 extending forwardly therefrom and terminating in open hooks and a rope holding element having trunnions engageable with said open hooks.

In testimony whereof I affix my signature. 45

JAY R. CORBETT.
